UNITED STATES PATENT OFFICE.

FRANK A. GOODALE, OF YOUE BET, CALIFORNIA.

ORE CLASSIFIER OR SEPARATOR.

1,201,956.

Specification of Letters Patent. Patented Oct. 17, 1916.

Application filed April 14, 1916. Serial No. 91,166.

To all whom it may concern:

Be it known that I, FRANK A. GOODALE, a citizen of the United States, residing at You Bet, in the county of Nevada and State of California, have invented new and useful Improvements in Ore Classifiers or Separators, of which the following is a specification.

This invention relates to ore classifiers or separators, and particularly to ore classifiers or separators of that kind in which the pulp is spread over a moving surface in such a manner as to effect the travel of the slimes or lighter material in one direction and the sand and other coarser material in a different direction, whereby the separatory action is secured.

The object of the invention is to provide a construction of classifier or separator by means of which a more reliable and efficient separation of the lighter from the heavier materials is obtained.

A still further object of the invention is to provide a classifier or separator embodying means for securing an efficient raking or spreading of the material over a separator deck or surface at predetermined intervals, while said surface is in motion, so as to keep the particles of material constantly loosened up and spread out for the separation of the lighter materials from the heavier ones.

A still further object of the invention is to provide a classifier or separator embodying stationary inclined decks or surfaces in connection with rotary and vertically reciprocatory rakes for loosening up and spreading out the material.

A still further object of the invention is to provide improved means for supplying wash water for a flushing action to assist in separating the lighter from the heavier material, and improved means for collecting the light and heavy products.

With these and other objects in view, the invention consists of the features of construction, combination and arrangement of parts hereinafter fully described and claimed, reference being had to the accompanying drawings in which:

Figure 1 is a vertical section through an ore separator or classifier constructed in accordance with my invention. Fig. 2 is a top plan view of the same. Fig. 3 is a sectional plan view on the line 3—3 of Fig. 1. Fig. 4 is a sectional plan view on the line

4—4 of Fig. 1. Fig. 5 is a vertical section on the line 5—5 of Fig. 1.

In the practical embodiment of my invention, I provide a suitable frame structure 1, which supports at its base an inner circular trough 2 to receive the separated slime and lighter materials, and an outer annular trough 3 to receive the sand and other heavier materials, from which troughs the separated materials may be removed or discharged in any preferred way. Projecting upward from the base of the frame centrally into and above the inner trough 2 is a socket bearing 4 in which is journaled the lower end of a hollow vertical shaft 5, which shaft is journaled at its upper end in a cap bearing 6 fixed to the upper portion of the frame, such bearings permitting the shaft 5 to both rotate and reciprocate vertically.

As shown, a worm gear 7 is mounted upon the upper end of the shaft and suitably held by a part of the bearing 6 against vertical motion, while said gear is permitted to revolve freely with the shaft. This gear has 80 its hub provided with a longitudinal key or feather 8 which engages a slot 9 in the shaft, by means of which a clutch connection is afforded adapting the shaft to be positively connected with the gear to revolve 85 therewith, while permitting the shaft to be vertically reciprocated through the hub of the gear. The gear receives motion from a worm 10 on a drive shaft 11 provided with fast and loose pulleys 12 for receiving motion from any suitable source of power. The means for reciprocating the shaft consists of a coupling head 14 swiveled to the shaft and having a stem 15 pivotally connected to one end of a double-armed yoke 90 16. This yoke is slotted to slidably engage a transmission shaft 17 and carries a roller 18 running in contact with an eccentric wheel or disk 10 on said transmission shaft 17, which shaft is journaled in suitable bearings 20 and connected with and driven from the worm shaft by a drive belt 21.

The swivel connection between the coupling head 14 and the shaft 15 comprises a head or flange 14' upon the end of the shaft 15 which fits within the upper end of the hollow shaft 5 and is engaged and held in position by the head 14. This head 14 is in the form of a cap fitting over upon the upper end of the shaft 5 and having an 110 opening for the passage of the shaft 15, in which said shaft 15 is free to turn, the head

or cap 14 being secured in position upon the shaft 5 by screws 14^a or other suitable fastenings.

Supported by the frame is a series of superposed separator decks or platforms 22, each made of sheet metal or other suitable material. Each of these decks or platforms 22 is of annular form and surrounds the central shaft, and each of said decks or platforms is fixed to brackets 23 secured to the frame structure 1. Each deck or platform 32 further inclines or slopes downwardly or inwardly toward the central shaft at a desired angle of inclination, and is separated 10 from the shaft and surrounding walls or timbers of the frame structure. At the lower end of each deck or platform is an up-standing vertical guard wall 24, which guard wall forms a dam adapted to prevent discharge of the coarser and heavier materials at the lower end of the deck, while permitting the pulp and other lighter materials to flow upward and over the upper edge of said dam or guard wall, the slime and other lighter materials thus being discharged by gravity downward into the trough 2.

Beneath each deck or platform 22, except the last one of the series, is a second deck or platform 25, each of which is also made of sheet metal and supported from the frame work by the brackets 23. The decks 25 have their outer edges projecting outwardly beyond the outer edges of the decks 22 and their inner edges terminating the same distance outwardly of the inner edges of the decks 22, and said decks 25 also incline or slope downwardly and inwardly toward the shaft 5, but at a somewhat greater pitch or angle than the decks 22. Each deck 25 receives the sand and coarse materials passing up along the surface of the superposed deck 22 and discharging over the outer edge of said deck 22, such material, except in the case of the use of but a single separator 40 deck 22, thence flowing downward by gravity along the deck 25 and over the inner edge thereof on to the next underlying deck 22, where a second separation of the character described occurs, any slime or lighter material which may have discharged with the coarser particles being discharged over the dam 24 at the lower edge of the second deck 22, while the coarser particles will pass on to the next underlying deck 25, and so on 50 throughout the series.

It will be understood from the foregoing description that the operation above described applies in the use of a classifier or separator having a plurality of superposed 60 separating decks or platforms, and that when the material finally reaches the last deck 22 of the series, which is located immediately above the troughs 2 and 3, the remaining slime and heavier particles will respectively discharge into said troughs.

Where but a single separator deck or platform 22 is employed, as in a simple form of machine, the parts will be arranged as shown with relation to the receiving troughs and lower deck 22, which will directly receive 70 the pulp and discharge the separated slime and heavier particles directly into the troughs.

The pulp is fed from a suitable source of supply to the upper deck 22 of the series 75 from one or more feed hoppers 26, and for the purpose of raking and spreading out the material contained upon each deck or surface 22 for the separating action, I provide for use in conjunction with each deck a rotary rake or scraper. Each of these rotary rakes or scrapers comprises rake bars 27 connected by hanger arms 28 with a wheel like frame composed of radial spokes 29 leading 80 from a central hub 30 composed of semi-circular sections united by bolts 32 by means of which the rake is detachably and adjustably secured to the shaft 5, so that the edges of the rake bars may be adjusted with relation to the surface of the deck 22 over which 85 said bars are movable. The rake bars are inclined to the same degree as the decks and in operation sweep over the surface thereof during a portion of their revolution, thus throwing the coarse particles of material 90 outwardly and upwardly toward the outer discharge edge of the platform, and at the same time separating the slime and lighter material therefrom and permitting the same to flow or work down toward the inner edge 95 of the deck and finally discharge over the dam 24. It will be evident from the foregoing description that during a portion of the revolution of the shaft the shaft will be in a lowered position, and in such position 100 of the shaft the rake bars will also be lowered down against the decks or platforms for a raking action, while during the remainder of the revolution of the shaft said shaft will be elevated and will likewise elevate the rake bars so that they will move clear of and over the surface of the material. Provision is thus made for an efficient 105 spreading or raking action and also at the same time for an interval of rest during 110 which the material will gravitate and tend to separate according to its different specific 115 gravities, in preparation for the gradual and advancing steps in the process of separation.

For the purpose of facilitating the flow 120 of the material and the separation of the finer from the coarser material, I provide means for supplying wash water to flow down the surfaces of the decks 22 and 25, thus washing out the finer material and 125 effect a freer discharge of the same with the wash water over the dam 24. The means employed for this purpose comprises perforated spray pipes 31 receiving the water from any suitable source of supply and hav- 130

ing its perforations arranged to discharge the water in the form of a spray down upon the surface of the pulp lying on each deck 22. A sleeve 32' is carried by the hub of 5 the lower rake and telescopes over the bearing 4 to prevent the material discharging into the trough 2 from passing down into said bearing 4.

From the foregoing description taken in 10 connection with the drawings, the construction and mode of operation of my improved classifier or separator will be readily understood, and it will be seen that the invention provides a device of this character which is 15 not only simple of construction but which is adapted to effect a thorough classification or separation of the particles of material from each other and to discharge the same in separate receptacles, and furthermore a 20 more efficient separatory action is obtained by the described mode of raking or spreading out the material and providing for the separation and discharge of the heavier and lighter products in the manner de- 25 scribed. Of course it is to be understood that one or more decks or platforms 22 may be employed, and that when two or more of such decks are employed the intervening decks 25 will be used in conjunction there- 30 with.

I claim:—

1. In an ore separator or classifier, the combination of a vertical shaft, a separator deck arranged concentric with the shaft, a 35 rake rotatable with the shaft for coöperation with said deck, and means operable in the action of the apparatus for moving the rake in vertical planes into and out of contact with the surface of the deck, one or 40 more times on each revolution of the shaft.

2. In an ore separator or classifier, a central shaft, a separator deck mounted concentric with said shaft, means for rotating said shaft, a rake arranged for rotation with 45 the shaft, and means for reciprocating the shaft to move the rake in vertical planes into and out of contact with the surface of the deck one or more times in each revolution of the shaft.

50 3. In an ore separator or classifier, a cen-

tral shaft, a separator deck arranged concentric with the shaft, a rake carried by the shaft for coöperation with the deck, means for rotating the shaft, and cam mechanism for reciprocating the shaft for moving the 55 rake in vertical planes into and out of contact with the surface of the deck one or more times in each revolution of said shaft.

4. In an ore separator or classifier, a central shaft, a separator deck having a surface 60 sloping downwardly and inwardly toward said shaft and having an upright wall at its inner edge, a rake carried by the shaft for coöperation with said deck, means for rotating the shaft, and means for reciprocating 65 the same for moving the rake into and out of contact with the surface of the separator one or more times in each revolution of the shaft.

5. In an ore separator or classifier, a central shaft, a separator deck having a surface inclining downwardly and inwardly toward said shaft, and having an upright dam wall at its inner edge, a rake carried by the shaft for coöperation with said deck, gear- 70 ing for rotating the shaft, a second shaft, and means actuated by said second shaft for reciprocating the first-named shaft for moving the rake in vertical planes into and out 75 of contact with the separator one or more times in each revolution of the central shaft.

6. In an ore separator or classifier, a central shaft, a separator deck arranged concentric with the shaft, a rake carried by the shaft for coöperation with the deck, means 80 for rotating the shaft, a reciprocating member swiveled to the shaft, and cam mechanism for reciprocating said reciprocating member and transmitting corresponding motion to the shaft, for moving the rake in vertical planes into and out of contact with the 85 surface of the deck, one or more times in each revolution of the shaft.

In testimony whereof I affix my signature in presence of two witnesses.

FRANK A. GOODALE.
